UNITED STATES PATENT OFFICE

128,179

DESIGN FOR A BOTTLE

Philip Schwartz, Springfield, Mass.

Application April 21, 1941, Serial No. 100,539

Term of patent 14 years

To all whom it may concern:

Be it known that I, Philip Schwartz, a citizen of the United States, residing at Springfield, in the county of Hampden and State of Massachusetts, have invented a new, original, and ornamental Design for a Bottle, of which the following is a specification, reference being had to the accompanying drawing, forming part thereof.

The figure is an elevational view of a bottle showing my new design.

The bottle is of circular cross section throughout.

I claim:

The ornamental design for a bottle, as shown and described.

PHILIP SCHWARTZ.
